C. F. Blake
ATTORNEY

UNITED STATES PATENT OFFICE.

GEORGE SHETOKIN, OF PORTLAND, OREGON.

CAMPING OUTFIT.

1,224,098.

Specification of Letters Patent. Patented Apr. 24, 1917.

Application filed September 14, 1916. Serial No. 120,077.

To all whom it may concern:

Be it known that I, GEORGE SHETOKIN, a subject of the Czar of Russia, residing at Portland, county of Multnomah, State of 5 Oregon, have invented certain new and useful Improvements in Camping Outfits, of which the following is a specification.

My invention relates to camping outfits in general, and particularly to camp furniture that may be compactly folded and several pieces combined to form a carrying case or bundle.

In general my invention consists of a table that may be folded into a box that may 15 be used for the transportation of supplies, and two or more seats or benches that may be folded so as to combine with said box to form a compact and convenient bundle.

I am aware that tables that fold up to 20 form a box have been used heretofore, and also that tables and benches have been combined and folded to form a box, but all such combined devices have possessed the common fault and disadvantage that the box 25 feature of the device disappears when the device is unfolded to be used as a table and benches.

The object of my invention is therefore to produce a combined device that may be 30 transported as a convenient bundle and supply case, and that may be unfolded and transformed into a table and benches without in any manner disturbing the supply case or box, and also to provide in such 35 a combined device simple, economical, and convenient construction.

I accomplish the above objects by means 40 of the construction illustrated in the accompanying drawing, which therefore becomes a part of this application for Letters Patent, like characters of reference indicating 45 like parts throughout the several views, in which;

Figure 1 is a perspective view of my com- 50 bined device folded for transportation.

Fig. 2 is a perspective view of the com- 55 bined table and supply case or box in folded position with the benches removed, parts being broken away to illustrate the construction.

Fig. 3 is a perspective view of my device 60 unfolded, showing the table and one of the benches as set up for use.

Fig. 4 is a detail perspective view of the 65 cover for the box or supply case.

Fig. 5 is a perspective view of my device

partially unfolded, and illustrating a modified form of use for my device.

The body of my device consists of a rectangular box or case having sides 6, ends 7 60 and bottom 8.

The body or box also has a top 9 having an opening therein which is closed by a removable cover 10.

Cleats 11 are provided upon two sides of 65 said opening to support the cover 10 when the same is in place.

The ends 7 and sides 6 project downward beyond the bottom 8, as shown in Fig. 2, for the purpose of providing a pocket or recess 70 wherein may be disposed the legs 12 when the same are in folded position.

Table leaves 13 are hinged to the sides 6 at the upper edges thereof, and are adapted to open out flat and flush with the top 9 to 75 form therewith a convenient table top.

The legs 12 are attached by pivots 14 to the body sides 6, and are securely braced by cross braces 15 and diagonal braces 16, the latter being detachable in any convenient 80 manner for the purpose of folding the legs into the above mentioned recess provided for the same.

Such folding legs are in common use upon many types of folding tables and other articles of furniture, and being well known to the art need no extended description or illustration.

It will be observed that the table portion of my device when folded up, as in Fig. 2, 90 assumes a rectangular form with no projecting parts, and that when unfolded and set up the box or supply case remains undisturbed, and may be easily and conveniently reached and entered by removing the 95 cover 10.

To render my device of still greater utility and convenience I provide therewith folding benches of peculiar and novel construction that adapts the same to be folded 100 and combined with the folded table to form a compact and convenient package or bundle of rectangular form having no projecting parts, as shown in Fig. 1.

The construction of these seats or benches 105 is illustrated in Fig. 3, wherein 17 is the top or seat, having hinged thereto at each end thereof an angle shaped member, the horizontally disposed legs 18 of said angle members being adapted to form extensions 110 of seat 17, and the vertically disposed legs of said angle members being adapted to

form the legs or supports 19, said angle members being braced in open position by diagonal braces 20 adapted to be detached and folded with the bench.

* 5 When the braces 20 are detached and the legs 19 folded over upon the seat 17, the portions 18 assume a position substantially normal to seat 17, and the distance between said portions 18 as thus folded is made substantially equal to the length of side 6 of the table.

The result of this construction is that when the benches are folded they will nest up with the folded table, the portions 18 15 forming flanges that project over the ends 7 of the folded table, thus preventing the folded benches from moving endwise relatively to the folded table.

A strap 21 is passed around the nested 20 benches and table which are thus secured against relative sidewise movement, and are formed into a neat, convenient and compact bundle or package for transportation, a handle 22 being provided for this purpose.

25 It will be observed that by this simple construction the inside of the box or supply case is entirely without any operating parts and is otherwise entirely unobstructed and in conformity with all the characteristics 30 of an ordinary rectangular box.

When desired the use of the benches may be dispensed with and the table used as a picnic lunch table without unfolding the legs, as illustrated in Fig. 5.

35 My invention may be made of any size and constructed of any material deemed convenient and suitable for a device of this character, and while I have illustrated and described a form of construction and arrangement of parts found desirable when materializing my invention, I wish to include in this application for Letters Patent 40 all mechanical equivalents and substitutes that may fairly be considered to come 45 within the scope and purview of my invention as defined in the appended claims.

Having disclosed my invention so that others skilled in the art may be enabled to construct and to use the same, what I claim as new and desire to secure by Letters Patent is:

1. In a camp outfit, a box like structure; a cover for said box; members hinged upon said box adapted to fold over upon said cover or to unfold substantially flush with 55 said cover to form a table top therewith; legs pivotally attached to said box and adapted to fold into a recess in the bottom of said box; in combination with benches comprising a seat member; an angle member 60 hinged to each end of said seat member adapted to fold up and nest with said box, one leg of each of said angle members projecting over the end of said box when nested therewith. 65

2. In a camp outfit, a folding table and supply receptacle in combination with benches comprising, seats; legs pivotally attached to the ends of said seats; and edge members attached to the ends of said seats 70 and adapted to encompass said folding table when said legs are folded against said seats and the benches and table are nested together.

3. In a camp outfit, a folding table and 75 supply receptacle in combination with seats; angle members hinged to the ends of said seats, one leg of each of said angle members forming extensions to said seats, and the other legs of said angle members forming 80 supports for said seats, said seats and angle members nesting compactly with said table when folded.

In witness whereof I claim the foregoing as my own I hereunto affix my signature in 85 the presence of two subscribing witnesses, at Portland, county of Multnomah, State of Oregon, this 31st day of Aug. 1916.

GEORGE SHETOKIN.

Witnesses:
